UNITED STATES PATENT OFFICE.

WILLIAM W. DEAN, OF CHICAGO, ILLINOIS, ASSIGNOR, BY MESNE ASSIGNMENTS, TO BENJAMIN ELECTRIC MANUFACTURING COMPANY, OF CHICAGO, ILLINOIS, A CORPORATION OF ILLINOIS.

ELECTRIC SWITCH.

1,258,539.

Specification of Letters Patent. Patented Mar. 5, 1918.

Application filed July 18, 1913. Serial No. 779,727.

To all whom it may concern:

Be it known that I, WILLIAM W. DEAN, a citizen of the United States, residing at Chicago, in the county of Cook and State 5 of Illinois, have invented new and useful Improvements in Electric Switches, of which the following is a full, clear, concise, and exact description, reference being had to the accompanying drawing, forming a 10 part of this specification.

The present invention relates generally to electric switches of the pressure-operated type, and more particularly to switches of this class which can be positively operated 15 without the exercise of special care or attention on the part of the user.

Such switches are especially applicable to situations where the time and attention of the operator are taken up with other matters and a minimum only can be given to the operation of the switch, as, for example, in the case of the control switch of an electric horn of an automobile. They are also desirable in other situations where for any 25 reason the operating pressure cannot be carefully applied.

One object of the present invention is to provide a switch of this readily operable character in which the pressure-operated 30 member may be tilted about a central universal joint to make and break circuit in all instances. Another object is to provide a switch which shall be comparatively weather-proof under the usual conditions of 35 automobile service. Another object is to provide a switch which is simple in construction and economical to manufacture. These and other objects and advantages of my invention will be more fully understood 40 upon reference to the following detailed description taken in connection with the accompanying drawing, and the scope of the invention will be particularly pointed out in the appended claims.

45 In the drawing—

Figure 1 is a general perspective view of a portion of an automobile equipped with a switch constructed in accordance with my invention;

50 Fig. 2 is a vertical section of a switch constituting one form of the invention, illustrating also the manner of attaching the same to the spoke of an automobile steering wheel, the section being taken on a plane indicated by the line 2—2 of Fig. 3;

Fig. 3 is a horizontal section taken on a plane indicated by the line 3—3 of Fig. 2;

Fig. 4 is a vertical section of a modified form of the invention, the section being taken on a plane indicated by the line 4—4 60 of Fig. 5; and

Fig. 5 is a horizontal section of this latter form of the invention taken on a plane indicated by the line 5—5 of Fig. 4.

Throughout these views like characters 65 refer to like parts.

Referring to the form of invention illustrated in Figs. 2 and 3, 10 designates a casing, 11 an insulating base, 12 and 13 electrical contacts, 14 a pressure-operated member for actuating the contacts, and 15 a post having a universal joint connection with the member 14 and a fixed connection with the insulating base 11, which with the casing 10 forms a support for the other parts. 70 The casing 10 is preferably of fiber or other suitable insulating material. The electrical contact 12 is in the form of a ring having a horizontal flange by which it is secured to the base 11, preferably by screws 75 16. The co-operating contact 13 is preferably composed of a pair of plates which are pressed outward from each other at the center so as to form a socket 17 for the reception of the ball 18 upon the upper end 80 of the post 15. The plates of the contact 13 are secured to the member 14 in any suitable way, as by means of the screws 19. The periphery of the member 14 overhangs the adjacent walls of the cup 10 and is slightly 85 spaced therefrom so that it may be readily tilted about the center fulcrum formed by the universal joint by pressure peripherally applied, that is any pressure which is off center. Engagement of the contacts 12 and 90 13 as a result of the tilting movement of the member 14, will limit the movement of the latter. A coiled spring 20 surrounds the post 16 and co-acts between the pressure-operated member 14 and the base 11 so as 95 to maintain the member 14 in its normal position, in which the contacts 12 and 13 are electrically separated. The post 15 is electrically connected at its lower end to the terminal 21 and thus conductively unites 100 the switch contact 13 with said terminal. Conductors 22 and 23 connect with the contact 12 and with the terminal 21. These connections may be established in any preferred way, as by inserting the end of the 110

bared wire in each instance through an opening, and soldering it in place. Conductors 22 and 23 pass through a stuffing-box 24 formed at an adjacent side of the casing 10. When used upon an automobile, the switch is preferably secured to a spoke 25 by a strap 26 of suitable material, which embraces the spoke and is secured at its ends to the switch by screws 27, which preferably pass through the casing 10 into the base 11 so as to hold the parts together.

In the form of the invention illustrated in Figs. 4 and 5, the central post is rigidly secured to the pressure-operated member 14 and the universal joint is made with the base or support of the switch, and the switch contacts are reversed in position. In this instance, the rigid connection between the post 15 and the pressure-operated member 14 is made by screwing the former into the latter, and the universal joint connection between the opposite end of the post 15 and the support is made by bulging the plates of the contact 13' so as to form a socket 17' for the ball 18', just as in the first instance. In this case, however, the contact 13' is secured to the base 11 instead of the pressure-operated member 14. As illustrated, this connection is made by screws 19'. Contact 12' is similar in construction to the contact 12, but is connected to the pressure-operated member 14 instead of to the base 11. Screws 16' serve to make this connection. In this instance conductor 22' is connected to the ring 12' and conductor 23' to a terminal 21' formed on one edge of one of the plates of the contact 13'. These conductors, as before, pass through a stuffing-box 24 formed upon the casing 10. In this form the switch is not shown attached to the steering wheel of an automobile, but it may be secured thereto just as in the previous form. When not thus secured, the casing 10 and base 11 are preferably connected together by screws 28.

The operation of each of these forms will be readily understood from the previous descriptions. In one case the pressure-operated member 14 will be tilted about a fulcrum at the upper end of the connecting post, and in the other case, about a fulcrum at its lower end. Circuit in each instance will be completed between the ring and plate contacts, and the tilting movement of the contact-operating member will be limited by the engagement of the contacts.

In Fig. 1 I have illustrated my invention applied to an automobile 30. The switch, designated 31, is mounted on the spoke 26 of the steering wheel 32, in convenient reach of the hand of the driver. Its contacts are included in circuit with the electric horn 33 and the electric battery, magneto or other source of current.

Although I have illustrated my invention in connection with the horn circuit of an

automobile, it will be understood that the same is capable of various other uses. It will also be understood that the present disclosure may be modified and altered in many respects without departing from the spirit and scope of the invention. I therefore do not wish to be limited to the particular use and disclosure herewith presented, but aim to cover by the terms of the appended claims the various uses and alterations and modifications of structure which properly come within the scope of my invention.

Having thus described my invention, what I claim as new and desire to secure by Letters Patent is—

1. An electric switch comprising coöperating switch contacts in substantially parallel planes, and a universal spacing joint connection between said contacts for holding said contacts a constant distance apart at said connection while permitting a relative tilting movement therebetween to enable said contacts to engage at different points upon the application of operating pressure at different places thereon.

2. An electric switch comprising coöperating switch contacts having annular contact surfaces and a universal spacing joint connection between them, one of said contacts being tiltable with respect to the other while being held at a constant distance therefrom at said connection.

3. An electric switch comprising coöperating switch contacts having annular contact surfaces, a universal spacing joint connection between said contacts, one of said contacts being tilttable with respect to the other while being held a constant distance therefrom at said connection, and means for normally and yieldingly holding said contacts out of engagement.

4. An electric switch comprising coöperating switch contacts having annular contact surfaces, a universal spacing joint connection between said contacts, one of said contacts being tilttable with respect to the other while being held a constant distance apart at said connection, and a coil spring for holding said contacts normally out of engagement.

5. An electric switch comprising a support, a substantially parallel actuating member, a mechanical connection for maintaining said support and member a constant distance apart at the point of connection and allowing a universal tilting movement of one relative to the other, and coöperating switch contacts on said support and member.

6. An electric switch comprising a casing, coöperating switch contacts within said casing, a contact-actuating member normally in proximity to said casing, responsive to peripheral pressure to operate said contacts and limited in its movements by peripheral portions of said contacts; and a mechanical

connection for maintaining said member a constant distance from said casing at the point of connection and allowing a universal tilting rocking movement of said member relative to said casing.

7. An electric switch comprising a base member, a contact thereon, a non-flexible operating member substantially parallel with said base member, a contact thereon, a central rigid spacing post between said members preventing rectilinear movement of the operating member and on which one of said members has a universal tilting movement when pressure is peripherally applied thereto to operate said contacts, and a spring for maintaining said contacts normally in substantially parallel relation.

8. An electric switch comprising a casing, a contact mounted in said casing, a flat non-flexible top over said casing normally out of engagement with the sides of said casing, a contact on said cover, a central spacing post in said casing preventing rectilinear movement of said top and on which said top rocks when peripheral pressure is applied thereto at any point of the periphery for operating said contacts, and a spring for maintaining the periphery of said cover normally spaced from said casing.

9. A switch comprising an insulating base member, a substantially flat non-flexible operating member, a rigid central post between

said base member and operating member preventing rectilinear movement of said operating member and on which said operating member rocks when pressure is peripherally applied at any point thereof, a cup-shaped contact and a contact having annular contact surfaces for co-operating with said cup-shaped contact mounted on said members, and a spring for maintaining said members normally substantially parallel.

10. A switch comprising an inclosing casing having circular sides, an insulating base mounted within said casing, a central post mounted within said casing, a non-flexible cover member mounted upon said post and prevented from rectilinear movement thereby and having its periphery spaced from the sides of said casing, a cup-shaped contact and a contact having an annular co-operating contacting surface, one mounted in said casing and the other mounted on the under side of said operating member, and a spring for maintaining the said contacts normally spaced apart.

In witness whereof, I have hereunto subscribed my name in the presence of two witnesses.

WILLIAM W. DEAN.
